UNITED STATES PATENT OFFICE.

BRUNO LEHNERT, OF COPENHAGEN, DENMARK.

DESIGN FOR A BAG.

Application filed January 5, 1925. Serial No. 11,924. Term of patent 3½ years.

To all whom it may concern:

Be it known that I, BRUNO LEHNERT, a citizen of the Republic of Czechoslovakia, residing at Copenhagen, Denmark, have invented a certain new, original, and ornamental Design for a Bag, of which the following is a specification, reference being had to the accompanying drawings, forming part thereof, in which—

I claim:

The ornamental design for a bag as shown.

BRUNO LEHNERT.
